(57) **CLAIM**

The ornamental design for a storage battery, as shown and described.

DESCRIPTION

1. Storage battery

1.1 : Front

1.2 : Back

1.3 : Top

1.4 : Bottom

1.5 : Left

1.6 : Right

1.7 : Front perspective view

1.8 : Back perspective view

1.9 : Front-top perspective view

The parts shown in dotted lines do not form part of the claimed design; thin lines shown on the surface of the design in the front perspective view, the back perspective view and the front-top perspective view illustrate the shape of a three-dimensional surface.
